UNITED STATES PATENT OFFICE.

NELSON J. RUSSELL, OF CHICAGO, ILLINOIS.

FUEL-SAVING DEVICE FOR FURNACES.

Application filed January 12, 1923. Serial No. 612,802.

To all whom it may concern:

Be it known that I, NELSON J. RUSSELL, a citizen of the United States, residing at Chicago, in the county of Cook and State of Illinois, have invented certain new and useful Improvements in Fuel-Saving Devices for Furnaces, of which the following is a specification.

This invention relates, generally, to improvements in furnaces, but particularly to devices for feeding air to furnaces, and especially to that type of furnaces known as boiler furnaces, wherein a boiler having a plurality of spaced flues for the passage of flames, heat and gases from the fire-box or fire-pot, is employed, and it consists in certain peculiarities and novel features of the construction, combination and arrangement of the various parts thereof as will be hereinafter more specifically claimed.

Broadly speaking, the object of the invention is, the provision of certain improvements and devices applicable to or used in connection with boiler-flues or fire-flues of a furnace, for augmenting the effective power of fuel for heating purposes, and also for the generation of steam.

More specifically, an object of the invention is to provide a device for automatically admitting, heating and discharging atmospheric air into furnaces, in such a manner that the supply of air to the furnaces, will, through the medium of the device, be heated to a high degree of temperature, and in such a condition discharged or distributed in the fire-box or pot thereof, to commingle with the combustible and volatile gases emanating from the burning fuel, where said heated air and oxygen will be utilized to increase from a given amount of fuel, the combustion of the combustible gases, or of the free carbon released during the burning of such fuel, thereby avoiding to a marked degree the formation of smoke, yet attaining a maximum amount of heat units from the fuel.

While I have shown in the accompanying drawing a device embodying my improvements applied to a horizontally mounted boiler, and will hereinafter so describe it, yet it will become obvious from the following description and explanation, that the device is applicable to boilers whether their flues are of the upright, diagonally disposed, or horizontal type, and for this reason, I do not desire to be limited, except where so

mentioned, in the annexed claims, to any particular type of boiler furnace.

In the accompanying drawing—

Fig. 1 is a cross-sectional view taken on line 1—1 of Fig. 2, as indicated by the arrows, of a portion of a boiler, illustrating the same equipped with a fuel saving device embodying the invention.

Fig. 2 is a longitudinal central sectional view through the furnace and boiler, and

Fig. 3 is a greatly enlarged longitudinal sectional view of one of the boiler flues, showing it equipped with the fuel saving device.

Corresponding numerals of reference refer to like parts throughout the different views of the drawing.

The furnace casing as a whole is designated by the numeral 5, and as usual, has at its front end a fire-box 6, and at its rear end another chamber 7, which will herein be termed the combustion chamber, from which leads an outlet flue or pipe 8^a for the discharge of smoke and unconsumed particles of combustion. The fire-box 6 is of course provided as usual, with a grate not shown, and said box or chamber is located at the front end of the boiler 8 which is horizontally mounted in the usual or any preferred way within the casing between the chambers 6 and 7, and has as shown, a plurality of fire-flues 9 which are spaced from one another and surrounded by water within the boiler. One of the flues 9, by preference located centrally with respect to the group of flues, has its rear end closed in any suitable manner but usually by means of a plug 10 of asbestos or some other substantially non-combustible material.

Extended through the upper portion of the furnace casing 5 rearwardly of the rear end of the boiler 8 into the combustion chamber 7, is an air intake pipe 11 which has connected by means of a coupling 12, a branch pipe 13 which is extended through a centrally disposed orifice in the plug or closure 10 and has mounted on its end within the flue 9 an annular chamber casing 14 of less diameter than the inner diameter of the said flue. The casing 14 has extended centrally from its front end a tube 15 which communicates at its front end with another chamber casing 16 which is also annular in shape and of less diameter than the inner diameter of the flue 9 in which it is located.

The casing 14 is provided in its periphery

with one or more openings 16^a, and in its front wall with one or more openings 17 for the discharge of air from said casing into the flue 9 in which it is located. The casing 16 at the front end of the flue 9 is provided with a central discharge opening 18 and around said opening with a concave depression 19 for the purpose of causing air discharged through the opening 18 to be spread 10 in a circular volume.

As is more clearly shown in Fig. 3 of the drawing, the casing 16 is of considerably larger capacity than the casing 14 and is located within the tube 9 in such a way 15 that its front end is about flush with the front end of the flue 9 and so that an annular space is provided between the annular wall of the casing 16 and the inner surface of said flue. The rear wall of the casing 16 20 occupies a position at right angles to the flue 9 and thus provides an abutment against which air traveling forwardly or in the direction indicated by the arrows in Fig. 3, will impinge and to a certain extent 25 be impeded in its passage through the space between the casing 16 and flue. The casing 14 is as shown located near the rear end of the flue 9 and will be supplied with atmospheric air through the intake pipe 11 30 and branch pipe 13, which as before stated, is extended through an opening in the closure 10 and as shown, supports the casing in such a way that its annular wall will be spaced from the inner surface of the flue 35 9 in which the device is located.

The operation of the device is simple and as follows:

The draft through all of the flues 9 of the boiler, with the exception of that one or 40 those equipped with the device, for it will be understood that I may employ my improved device in one or more of the boiler flues, will be, as usual, from the fire-box 6 rearwardly through the flues, but as the flue 45 or flues equipped with the device has it or their rear ends closed, it is manifest that the draft through such equipped flue or flues, will be reversed as the flames and heated gases escaping rearwardly from the fire-box 50 6 through the flues surrounding the flue or flues equipped with the device, will create a forward suction at the front end or ends 55 of the equipped flues and that thus a forwardly pulling draft will be supplied to the front ends of the equipped flue or flues. This action, together with atmospheric pressure, will cause air to enter the outer end of the intake pipe 11 and pass into the primary expansion chamber 14 where it will become 60 heated and expanded by reason of the heat of the water surrounding the flues, as well as by reason of the heat in the combustion chamber 7 and also by reason of the heat imparted from the surrounding flues. When 65 thus heated and expanded, air will pass

from the primary expansion chamber 14 through the openings 16 and 17 into the cavity of the flue 9 and travel forwardly in the direction indicated by the arrows until it impinges against the rear wall of 70 the main or discharging expansion chamber 16 and from thence will pass out through the annular space between the casing 16 and flue 9 with considerable force and in a circular volume. 75

During this operation, part of the volume of air from the chamber 14 will pass through the tube 15 into the casing 16, where it will be further heated and expanded and from whence it will pass through the opening 18 into the fire-box. As the opening 18 is surrounded by a concave depression 19, this central volume of air will be caused to spread out in circular form and intersect the annular or circular volume of air discharged between the casing 16 and front end of the flue. The intersection of these volumes of air will set up agitation in the fire-box and cause commingling of the heated air and combustible and volatile 85 gases emanating from the burning fuel, thus utilizing the air and oxygen to increase from a given amount of fuel the combustion of the combustible gases. 90

While I have shown in the drawing, the 95 air intake pipe 11 as being vertically extended through the top of the furnace and in communication at its lower end with one of the flues of the boiler, yet it is manifest that the intake pipe may be extended 100 through one of the side walls of the furnace or through the rear end wall thereof and connected to one of the flues, and that the same results will be afforded.

It will further be understood that while 105 I prefer to utilize one or more of the fire flues of a boiler in connection with my improved device, yet I do not wish to be limited thereto, as a fire flue of the furnace which may be suitably located, may be employed as a receptacle for the expansion casings and the connecting pipe therefor and have its end opposite the fire-box closed in the same manner as when the device is used in connection with a boiler 110 115 flue and as above described.

Having thus fully described my invention, what I claim as being new and desire to secure by Letters Patent is—

1. In a device of the class described, the 120 combination with a furnace having a fire-box, of a conduit having one of its ends open and its other end closed, the open end of said conduit being adjacent the fire-box, an air intake pipe communicating at one of its 125 ends with the conduit near its closed end and having its other end disposed for the intake of air, an apertured casing located in the conduit near its closed end in communication with said pipe, another casing lo- 130

cated in the open end of the conduit and having means for discharging air forwardly therefrom, and a pipe connecting the said casings.

5 2. In a device of the class described, the combination with a furnace having a fire-box, of a conduit having one of its ends open and its other end closed, the open end of said conduit being adjacent the fire-box, an 10 air intake pipe communicating at one of its ends with the conduit near its closed end and having its other end disposed for the intake of air, an apertured casing located in the conduit near its closed end in communication with said pipe, the said casing being spaced from the walls of the conduit, another casing located in the open end of the conduit and having means for discharging air forwardly therefrom, said last named 16 casing being spaced from the walls of the conduit and having communication with the first named casing.

3. In a device of the class described, the combination with a furnace having a fire-box, of a boiler provided with a plurality of flues and located with one of its ends adjacent the fire-box, at least one of said flues having its end opposite the fire-box closed, an air intake pipe communicating at one of its ends with said flue near its closed end and having its other end extended through the furnace casing for the intake of air, an apertured casing located in said flue near its closed end in communication with said pipe, said casing being spaced from the walls of the flue, another casing located in the open end of the flue and having means for discharging air forwardly therefrom, said last named casing being spaced from the walls of the 22 said flue and having communication with the first named casing.

4. In a device of the class described, the combination with a furnace having a fire-box at one of its ends and a combustion chamber at its other end, of a boiler provided with a plurality of flues and located longitudinally between said fire-box and the combustion chamber, at least one of said flues having its end adjacent the combustion chamber closed, an air intake pipe communicating at one of its ends with said flue near its closed end and having its other end extended through the furnace casing for the intake of air, an apertured casing located in said flue near its closed end in communication with said pipe, said casing being spaced from the walls of the flue, another casing located in the end of the flue adjacent the fire-box and having centrally in its front wall a forwardly flared opening, said last named casing being spaced from the walls of said flue and having communication with the first named casing.

5. A device of the class described, including in combination with a furnace having a fire box at one of its ends and a combustion chamber at its other end, a boiler provided with a plurality of longitudinally disposed flues, the said boiler being longitudinally located in the furnace with its ends spaced from the inner end walls of the furnace, an air intake pipe extending into the end of one of said flues adjacent the said combustion chamber and having its other end extended through the furnace wall for the intake of air, and means closing the end of said flue adjacent the combustion chamber around said pipe but leaving the inner end of said pipe open for the discharge of air into said flue.

NELSON J. RUSSELL.
